Specification for Design.

Patented July 26, 1921.

Application filed February 3, 1921. Serial No. 442,303. Term of patent 7 years.

To all whom it may concern:

Be it known that I, EDWARD A. FARR, a citizen of the United States, residing at Meriden, in the county of New Haven and State of Connecticut, have invented a new, original, and ornamental Design for Percolating-Urns, of which the following is a specification, reference being had to the accompanying drawing, forming a part thereof, in which—

Figure 1 is a front elevation of a percolating urn embodying my new design.

Fig. 2 is a side elevation of the same.

Fig. 3 is a plan view of the same.

I claim:

The ornamental design for a percolating urn, as shown.

EDWARD A. FARR.
